AFTER-TREATMENT OF YARN OF
ARTIFICIAL ORIGIN

Johann Joseph Stoeckly, Teltow-Seehof, and
Kurt Schmidt, Kassel-Bettenhausen, Germany,
assignors to North American Rayon Corpora-
tion, New York, N. Y., a corporation of Dela-
ware

Application October 1, 1936, Serial No. 103,558
In Germany October 5, 1935

6 Claims. (Cl. 8—158)

The present invention relates to the manu-
facture of yarn of artificial origin, but primarily
has to do with the after-treatment of artificial
silk yarn or staple fibre made therefrom.

- 5 In the manufacture of yarn of artificial origin, it is necessary to subject the freshly spun yarn to a thorough after-treating process consisting of deacidification, desulphurization, and/or decopping, bleaching, washing, reviving and the like.
- 10 The after-treatment of the yarn in the undivided state, i. e., in a continuous skein or bundle of threads, was heretofore carried out by leading the bundle of thread in a continuous operation through the various after-treating baths which
- 15 were contained in open vats or tanks and the like provided with spraying devices. The after-treatment of staple fibre, i. e., artificial silk cut up into small pieces of thread immediately after the spinning of the yarn, was generally carried out in apparatus provided with agitating devices simi-
lar to those used for the washing of wool.

Because these after-treatment processes necessitate the employment of a plurality of open vats or tanks, it is rather difficult and complicated
25 to recover the chemicals used in preparing the after-treating baths, while the process itself was very complicated and expensive.

The present invention has therefore for its object to provide a method and means which facilitate the after-treatment of artificial silk
30 in the form of continuous skeins or staple fibre.

Another object of the present invention is to provide a method and means which make it possible to carry out the after-treatment of artificial silk bundles or staple fibre with a minimum of chemicals.

Still another object is to provide a method and means which facilitate the recovery of the chemicals from the various discharged baths used for the after-treatment.

40 These and other objects will in part become obvious and will in part be pointed out in the following specification and appended claims, taken in conjunction with the accompanying drawings, in which—

Fig. 1 is a diagrammatic cross-sectional view of the new device; and Fig. 2 is a diagrammatic lay-out of an after-treating arrangement employing the new apparatus.

50 Referring now to the drawings and particu-
larly to Fig. 1, the new device comprises a tank
1 divided into three compartments 3, 5 and 6 by
means of two perforated horizontally positioned
plates 2 and 4. The after-treating liquid is fed
55 through pipe 7 and discharged through pipe 8, 9

is the cover of the tank which can be opened by means of the lifting ring 10.

The spun goods to be after-treated are inserted only in the compartment 5, and it is of im-
portance that this compartment is filled up only 5
to such an extent, that the increase in volume
caused by the after-treating liquid subsequently
introduced fills the compartment to capacity. It
was found, that in the case of cellulose threads
it is advisable to use about 6-12 kg. of filaments 10
calculated on a treating space of 100 liters ca-
pacity. If necessary, the aforementioned weight
limits may be either somewhat decreased or in-
creased.

Another factor which plays an important part 15
in the satisfactory after-treatment is the speed
at which the treating liquid is forced through
the yarn body. If the speed of flow is too fast, the
treating liquid is not utilized sufficiently and too
much liquid is required. If, on the other hand, 20
the speed of the liquid is too slow, the liquid tends
to mix with the subsequently introduced liquid,
and consequently the duration of treatment will
be too long. Speeds of flow of from 1 to 20 cm.
per minute, preferably from 5 to 10 cm. per 25
minute have given the best results. If the
quantity of goods placed in the tank is too small
in volume a high speed of flow of the treating
liquid will cause the goods to gather in the
upper portion of the tank, whereas if the speed 30
of flow is low the goods will tend to remain in
the bottom of the tank. In both cases the effi-
ciency of the apparatus is impaired. Only by
properly proportioning the volume of spun goods
and the speed of flow of the after-treating liquid
35 with respect to the capacity of the tank, is it
possible to completely fill up the tank without
leaving any open spaces therein, resulting in a
uniform distribution of the goods in the tank.
In some cases it was found advantageous to as-
sist in uniformly distributing the goods in the
tank by blowing finely dispersed air or inert
gases into the tank. The after-treating liquid
may be either fed to the tank continuously or
intermittently, and if more than one wash tank is
employed it is preferable to carry out the after-
treatment by the counter-current principle.

40 In the treatment of staple fibre the freshly spun
thread is first cut into the desired length and
then subjected to the after-treatment. Endless 50
skeins or bundles of yarn are preferably placed
in the tank in uniform layers. After the treat-
ment is finished the skein is reeled from the tank
beginning with the previously marked end piece
55 of the skein.

5 In order to more uniformly disperse the after-treating liquid supplied through the pipe 7, the holes in the plates 2 and 4 are varied in size. Those around the center of the plates are made smaller while those close to the edge of the plates are made larger in size.

10 For the more convenient insertion of the spun goods into the tank, perforated containers filled with the yarn may be used. The employment of these containers has the advantage that the yarn body as a whole can be moved from one tank into another. These perforated containers would eliminate the use of the two perforated plates 2 and 4; it is only necessary to provide supporting 15 means for the container in the tank.

20 Reference is now made to Fig. 2 of the drawings, in which the tank 1 is connected with liquid containers 18, 19, 20, 21, 22 and 23 by way of branch pipe lines 12, 13, 14, 15, 16 and 17 and a collective pipe line 11. The supply of liquid from the containers 18, 19, 20, 21, 22 and 23 is controlled by the valves 39, 40, 41, 42, 43 and 25 44. The collective pipe line 11 is also connected to a discharge pipe 24. The upper end of the tank 1 is connected to another collective pipe line 25 which by means of a branch pipe line 26 leads to a de-aerating device (not shown). Another branch pipe line 27 leads to the discharge pipe, while a third branch pipe line 28 leads to the 30 carbon bisulphide recovery plant 29. Three additional branch lines 30, 31 and 32 are connected to the regenerating plants 33, 34, and 35 for sodium sulphite, bleaching lye and soap, from where the recovered baths are returned to the 35 storage tanks 21, 22 and 23 by way of return pipe lines 36, 37 and 38.

Example of operation

40 80 kg. of freshly spun artificial viscose threads cut up into staple fibre, calculated on the cellulose content, are inserted in the middle compartment of the tank, thus lying between the two perforated plates. The capacity of this compartment is 1000 liters, whereby the distance between the two perforated plates is one meter and the 45 free cross-section of the tank is one square meter. After the upper perforated plate has been bolted and the cover of the tank closed, wash water is introduced into the tank from below. A total amount of 3600 liters of water is forced through 50 the goods in a uniform stream within a period of 50 minutes, which is discharged at the upper end of the tank. The water remaining in the tank after the supply thereof has ceased is discharged 55 at the bottom of the tank and is subjected to an acidity test. If it is found necessary, the washing process is continued for a short period of time, preferably through refilling of the tank with fresh water which is discharged a few minutes 60 later.

Having now set forth the invention as required by the Patent Office statutes, what is claimed is:

1. In a process for the after-treatment of yarn of artificial origin the step of only partially filling a compartment of a tank with such spun goods, passing uniformly distributed after-treating liquid from below through said spun goods, controlling the rate of flow of the treating liquid through said spun goods so that a uniform distribution of the goods in the said tank takes place and discharging the after-treating liquid from the upper end of the tank. 10

2. In a process for the after-treatment of yarn of artificial origin, the steps of placing from 60 to 120 kilograms of yarn in a tank having a capacity of 1000 liters, passing uniformly distributed treating liquid from below through said yarn, controlling the rate of flow of the treating liquid so that a uniform distribution of the goods in said tank takes place, and discharging the treating liquid from the upper end of the tank. 15

20 3. In a process for the wet-treatment of yarn of artificial origin, the steps of placing from 60 to 120 kilograms of yarn in a compartment for each 1000 liters capacity of said compartment, forcing treating liquid through the yarn from below, and controlling the rate of liquid flow so that the liquid level in the compartment is caused to rise from one to twenty centimeters per minute. 25

30 4. In a process of the class set forth, the steps of placing from 60 to 120 kilograms of yarn in a compartment for each 1000 liters capacity of said compartment, forcing uniformly distributed treating liquid upwardly through said yarn body, and controlling the speed of liquid flow so that the liquid level in the compartment rises from five to ten centimeters per minute. 35

45 5. In a process for the wet-treatment of yarn of artificial origin, the steps of placing approximately 80 kilograms of yarn in a compartment having a height of one meter and a capacity of 1000 liters, and then passing at a uniform rate of flow approximately 3600 liters of treating liquid upwardly through said yarn during a period of approximately fifty minutes. 40

50 6. In a process for the wet treatment of viscose threads cut up into staple fiber, the steps of placing approximately 80 kilograms of said threads in a compartment having a height of one meter and a capacity of 1000 liters, and then passing at a uniform rate of flow approximately 3600 liters of treating liquid upwardly through said threads during a period of approximately fifty minutes, the weight of said viscose threads being calculated on the cellulose content thereof. 55
